UNITED STATES PATENT OFFICE.

FREDERICK W. LETSCH, OF BALTIMORE, MARYLAND.

ASSEMBLING AND TRANSFER MECHANISM.

Application filed November 12, 1920. Serial No. 423,698.

To all whom it may concern:

Be it known that I, FREDERICK W. LETSCH, a citizen of the United States, and residing at Baltimore city, State of Maryland, have 5 invented certain new and useful Improvements in Assembling and Transfer Mechanism, of which the following is a specification.

This invention relates to assembling and 10 transfer mechanism for typographic machines and particularly machines of the character disclosed in my copending application, Serial No. 222,760, filed March 15, 1918.

15 The invention has for its object to provide improved mechanism for supporting a line of matrices and space bands while the same are being assembled and transferred to the casting mechanism of the machine 20 and more particularly a mechanism of the kind mentioned in which manual operations other than the mere depression of keys are obviated. Other objects are to provide improvements in various details of construction 25 by which mechanism of this kind is simplified and rendered more efficient and quiet in operation.

In the drawings accompanying this specification and forming a part thereof:

30 Figure 1 is a front elevation of my improved assembling and transfer mechanism;

Figure 2 is a plan view of the same, parts appearing in section;

Figure 3 is an enlarged front elevation of 35 a part of my improved mechanism showing particularly the means employed for supporting the front end of a line of matrices;

Figure 4 is an elevational view similar to that of Figure 3 showing the parts in a different position;

Figure 5 is a transverse sectional view on the line 5-5 of Figure 1;

Figure 6 is a transverse sectional view on the line 6-6 of Figure 1;

45 Figure 7 is a detailed plan view of a part of the matrix receptacle showing the dogs for supporting the rear matrix in the receptacle;

Figure 8 is a view in end elevation of the 50 mechanism employed for operating the transfer slide of my improved mechanism;

Figure 9 is a sectional view on the line 9-9 of Figure 8;

Figure 10 is a fragmentary view showing 55 part of the mechanism by which motion is transmitted to the transfer slide;

Figure 11 is a detailed view showing one of the cams employed in connection with the slide operating mechanism; and

Figure 12 is a sectional view on the line 60 12-12 of Figure 1.

Referring to the drawings in detail, 10 and 11 represent respectively fixed front and rear rails suitably secured to the frame of a machine and spaced apart to form at their 65 right hand ends a receptacle M for receiving matrices and space bands to form an assembled line. These rails extend at the left to a position adjacent the casting mechanism (not shown) of the machine and constitute the guides through which the assembled matrices are moved. The front rail 10 is of substantially the same width throughout its length and at its lower inner edge is provided with a continuous inwardly projecting rib 10^a. The rear rail 11 adjacent the receptacle is substantially the same width as the rail 10 and at its lower edge is provided with a rib 11^a. The left hand portion of this rail beyond the receptacle M is narrower than the rail 10 as appears from Figure 12 and such narrow portion has a rib 11^b formed thereon. The portion of the rail 10 to the left of the receptacle M is provided with an upper rib 10^j 75 in line with the rib 11^b of the rail 11 and also with an intermediate rib 10^k upon which the lower ends of matrices may rest while being transferred in case they have 80 been assembled in an elevated position as 85 hereinafter indicated.

The matrices and space bands are delivered to the receptacle M in any suitable manner as by means of the well known pulley and belt and star wheel 12 shown particularly in Figure 1, the matrices resting upon the projections 10^a, 11^a heretofore mentioned. The rail 10 at its rear portion or that adjacent the receptacle is slotted at 10^b, Figure 5, and a duplex rail 10^e engages in 100 this slot and extends into the receptacle for the purpose of supporting the matrices in an elevated position when casting in such position is desired. The duplex rail 10^e is arranged in line with the intermediate rib 10^k of the rail 10 and the same is carried by a lever 10^d which is pivoted to the rail 10 as shown at 10^e and a handle 10^f is provided for withdrawing this rail when it is 105 desired that the matrices rest upon the projections 10^a, 11^a. A supplementary duplex rail 10^g is also provided which engages in 110

the slot 10^b in the rail 10 and rests in line with the duplex rail 10^c, the duplex rail 10^e being suitably mounted so as to be withdrawn when desired. The rail 10 adjacent to the receptacle is also provided at its upper edge with a gate 10^h pivoted at one end as at 10ⁱ and provided with a suitable handle by which the gate may be swung on its pivot and access obtained to the assembled matrices.

The top of the rails 10 and 11 adjacent to the star wheel 12 is provided with pivoted dogs 10^l, 11^c which are held in position by suitable springs as shown in Figure 7. It will be understood that as the matrices drop in front of the star wheel they are pressed past the dogs 10^l, 11^c which serve to support the rear matrix of a line.

While matrices are being assembled in the receptacle M, the front end of the line is supported by means of a finger 13 as herein-after described, this finger being arranged to travel in a slot 11^d in the right hand portion of the rail 11.

The transfer slide of my improved construction comprises two members 14 and 15 which are adjustable relative to each other to permit assembling lines of different length as will later appear. The member 14 is provided with a dove-tailed rib 14^a and the member 15 which a suitable groove which engages this rib. The face of the rib 14^a is provided with a series of graduated notches or depressions of any desired scale which represent different lengths of line. A bolt 16 carried by the member 15 or a projection thereon is adapted to engage in the aforementioned notches this bolt being held in engagement with the rib 14^a by means of a coiled spring 17 which surrounds the same. The bolt 16 is provided with a handle or knob 18 by which the same may be withdrawn from the notches 14^a when relative adjustment between the members 14 and 15 is desired. The member 14 of the transfer slide is provided with ears 19 which slidably engage a rod 20 rigidly secured to the frame of the machine and this member is also provided with a wheel 21 which is adapted to travel on a second rail 22 also rigidly secured to the framework of the machine.

At its forward or left-hand end the member 14 of the transfer slide is provided with a ledge 23 slotted at 23^a upon which a block 24 is slidably mounted. A rod 25 is rigidly secured to this block and extends toward the rear or right-hand end of the member 14, this rod slidably engaging ears 26 secured to the top of the member 14. A coiled spring 27 surrounds the rod 25, this spring being secured at one end to the rod and at the other end to one of the ears 26 on the member 14. This spring serves to yieldingly hold the block 24 in its right hand

position or that shown in Figure 3 of the drawing.

A support 30 is pivotally mounted on the top of the block 24 and the finger 13 heretofore mentioned is rigidly secured to this support. A coiled spring 31 surrounds the pivot of the support 30 which spring tends to hold the finger 13 normally in position parallel to the rails 10 and 11. At certain times, however, the finger 13 is held in position at right angles to the rails 10 and 11 against the action of the coiled spring 31 and this is accomplished by means of a latch 35 pivoted to the block 24 and provided with a projection 35^a which is adapted to enter a recess 30^a formed in the lower end of the support 30. When in the position stated the finger 13 serves to support the front end of a line of matrices and space bands. The latch 35 lies in the slot 23^a of the ledge 23 and is normally pressed upwardly by means of a spring 36, which surrounds the pivot thereof.

It will be understood that when the latch 35 is withdrawn from engagement with the support 30 the finger 13 will move to a position parallel with the rails 10 and 11 under the influence of the springs 31. The latch 35 is disengaged from the support 30 by a suitable stop or abutment (not shown) when the transfer slide is moved to the left to carry an assembled line to the casting mechanism. The finger 13 is restored to its position at right angles to the rails 10 and 11 when the transfer slide moves to the right, this result being effected by means of a fixed stop S which is positioned to contact with a lug 13^a on the support 30 and rotate the same until the latch 35 engages the notch 30^a. When the parts are in this position the stop S will not interfere with the lug 13^a as the transfer slide is again moved toward the left.

It will also be understood that when no matrices are in the receptacle M and the transfer slide has moved to the right, the finger 13 will be positioned adjacent the star wheel 12 as shown in Figure 1 and that as the matrices accumulate in the receptacle M the finger 13 and the block 24 and the parts connected therewith will be moved toward the left by the action of the star wheel against the last matrix in the line. The motion of the finger 13 and the block 24 towards the left will, of course, be resisted by the coiled spring 27 heretofore referred to, so that the finger 13 forms a yielding abutment or support for the front end of a line of matrices while the same is being assembled and transferred.

In order to support the rear end of an assembled line of matrices while the same is being transported to the casting mechanism of the machine the following mechanism is provided. A vertically slidable

- finger 40 is mounted on the front end of the member 15 of the transfer slide, this finger engaging in a suitable guideway formed on said member and being normally positioned beneath the matrix receptacle M. A lever 41 is pivotally mounted at 41^a on the member 15 of the transfer slide and the front end of this lever engages a rearwardly projecting lug or ear 40^a on said finger 40. The rear end 41^b of the lever 41 projects some distance beyond its pivot point for a purpose hereinafter described. Near its rear end the member 15 of the assembler slide is provided with an upwardly projecting lug 42 which is adapted to engage a stop or abutment 43^a formed on the fixed plate 43 which limits the movement of the transfer slide to the right. A latch 44 pivoted at 45 is positioned to engage the front face of the lug 42 when the same contacts with the stop 43^a. The latch 44 serves to hold the transfer slide at the extreme limit of its movement toward the right, as shown in Figure 1 of the drawing.
- In order to permit movement of the transfer slide toward the left the latch 44 must be disengaged from the lug 42 and mechanism is provided to effect such disengagement and to simultaneously raise the finger 40 so that the same will be positioned to support the rear of the assembled line as the slide is moved. Such mechanism will now be described.
- The transfer slide as a whole is moved back and forth through the medium of a connecting rod or spring link 50 which is given a reciprocating motion from a slotted lever 51 pivoted at 52 to the frame of the machine and operated by a bell crank lever 53 which is also pivoted to a fixed point on the machine frame and provided with a part which projects into the slot of the lever 51. The bell crank lever 53 is operated by a connecting rod 54 to which motion is imparted in a manner hereinafter described.
- The rod 50 is connected to the member 15 of the transfer slide by a lost motion connection which comprises a swinging link 55 pivoted at 56 to said member 15, this member being provided with a front abutment 57 and a rear abutment 58 against which said link 55 contacts alternately as the slide is moved forward and backward.
- The link 55 carries a forwardly projecting portion 59 which is adapted to contact with the latch 44 and lift the same above the lug 42. This will occur when the link is swung forward against the abutment 57. During this motion of the link 55 the lower end thereof or any part suitably connected therewith will contact with the rear end 41^b of the lever 41 and move the same about its pivot to elevate the front end thereof and the finger 40.
- It will thus be understood that when the slide operating link moves toward the left the latch 44 will be released from the lug 42 and the finger 40 positioned to contact with the rear end of the assembled line and support the same as the transfer slide continues to move in the direction stated. The assembled line is thus transported to the casting mechanism. It will also be understood that when the slide operating link is moved toward the right to return the slide to its original position, the link 55 will be positioned against the abutment 58 thus permitting the lever 41 and finger 40 to drop by gravity to their normal position. As the transfer slide reaches its original position at the right the latch 44 will again engage the lug 42 and hold the slide in that position.
- The mechanism for operating the transfer slide of the present invention and for controlling the same is substantially like that in my prior application heretofore mentioned. This mechanism comprises a pulley 60 loosely mounted on a stub-shaft 61 rigidly secured to the frame of the machine, the pulley 60 being constantly rotated by a belt 62 driven from any suitable source (not shown) connected with the machine. On the shaft 61 at one side of the pulley 60 there is detachably mounted a cam cylinder 63 and on the other side a clutch sleeve 64 carrying a clutch disk 65 which is constantly urged toward the pulley 60 by a spring 66. When the spring 66 is free to press the clutch disk 65 against the pulley the pulley is pressed against the cam cylinder 63 and the clutch disk and cam cylinder rotate with the pulley. The cam cylinder 63 is provided with a cam groove 63^a in which there engages a roller secured to one end of a bell crank lever 63^b pivoted at 63^c to a fixed part of the machine, the other end of said bell crank lever being secured to the connecting rod 54 heretofore mentioned. The clutch disk 65 is normally held away from the pulley 60 by a pin 67 operating on a cam ring 68 fast on the hub of the clutch sleeve 64, the pin 67 being mounted on a lever 69 the forward end of which is connected by a link 70 with a starting lever or key 71 on the keyboard of the machine. It will be noted that when the upper end of the starting lever is pressed down the pin 67 will be withdrawn from the high point 68^a of the cam ring 68. If the clutch disk 65 is not otherwise restrained it will then spring into engagement with the pulley 60 and the cam ring 63 will make a complete revolution, causing movement of the bell crank lever 63^b and the connecting rod 54 which movement will result in advancing the transfer slide toward the casting mechanism of the machine and returning the same to its original position. One member of the transfer slide is provided with a projection

P which is adapted to contact with and move a lever L as the transfer slide moves toward the right. The movement of this lever L through suitable mechanism (not shown) causes the main cam shaft of the machine to make a single rotation as fully described in my said prior application. The upper end of the lever L has a jointed portion L' which is normally maintained in line with the lever by a spring L'' but which will yield and permit the projection P of the transfer slide to move toward the left without moving the lever. In the proper operation of the device the starting key 71 should be instantly released after being depressed and the pin 67 then resumes position to engage the high portion 68^a of the cam ring 68 and disengage the clutch from the pulley after the completion of a single rotation of the cam cylinder. On the end of the clutch sleeve 64 there is secured a second cam ring 72 which cooperates with a pin 73 on a lever 74 to control the clutch disk 65 in the manner to be hereinafter explained, the cam disk 72 having a single high portion 72^a as shown in Figure 11. The opposite end of the lever 74 carries a roller 75 which runs on a cam 76 on the main cam shaft 77 of the machine, the cam 76 being circular with the exception of a high point 76^a.

The control of the clutch disk 65 and the parts operated thereby is effected in the following manner. Should the starting lever 71 be pressed before the main cam shaft 77 of the machine has completed its cycle or before the casting mechanism of the machine is in a position to receive an assembled line of matrices, the high point 76^a on the cam 76 which is fastened on the cam shaft 77 will not have reached a position to release the pin 73 from the cam ring 72, it being understood that the high point 72^a of this cam ring 72 is timed to be a trifle later in action than that of cam ring 68. Thus it will be seen that if the lever 71 is pressed prematurely, that is, before the main cam shaft 77 has come to a normal stop the clutch disk 65 will be restrained by the action of the pin 73 which will allow the transfer slide to move but a short distance at which point it will be held until the high point 76^a on cam 76 disengages the pin 73 from the high portion 72^a of the cam ring 72. When this point has been reached the slide will automatically move forward toward the mold position and complete its movement.

The function and mode of operation of the various parts of the mechanism have been set forth in describing the same and further description of the operation of the machine as a whole is thought unnecessary.

Various changes and modifications may obviously be made in the details of mech-

anism herein shown and described without departing from the spirit of the invention which is not limited to the precise construction disclosed.

Having thus described the invention what I claim as new and desire to secure by Letters Patent is:

1. In a mechanism of the kind described, means for receiving and supporting matrices to form a line, a transfer slide, a finger pivotally mounted on said slide and arranged to press constantly against the front matrix of a line while the line is being assembled and transferred, resilient means for yieldingly pressing said finger against the matrices, a second finger connected to and movable bodily with said slide and adapted to be positioned to support the rear end of an assembled line, and means to bodily move said slide and fingers to transfer the assembled line. 80

2. In a mechanism of the kind described, a receptacle for receiving matrices and space bands to form an assembled line, a transfer slide, a block slidably supported on said slide and carrying a finger pivoted thereon, said finger being adapted to be positioned against the front matrix of a line, resilient means on the slide for constantly pressing said finger against the front matrix of the line while the line is being assembled and transferred, a second finger on said slide normally positioned below the line receptacle, means for moving said last named finger upwardly to contact with the rear matrix of a line, and means for bodily moving said slide and fingers to transfer the assembled line. 100

3. In a mechanism of the kind described, a receptacle to receive matrices and space bands to form a line, means for pressing the line forward as successive matrices and bands are added thereto, a transfer slide, a block slidably mounted thereon, a finger pivotally mounted on the block and adapted to rest against the front matrix of a line, a spring for yieldingly pressing said finger against the front matrix of a line while the line is being assembled and transferred, a second finger slidably mounted on said slide, means for moving said second finger against the rear matrix of an assembled line, and means for bodily moving said slide and fingers to transfer the assembled line. 110

4. In a mechanism of the kind described, a receptacle to receive matrices and space bands to form a line, a transfer slide, a finger pivotally secured to said slide and arranged in the path of the matrices in the receptacle, resilient means on the slide for constantly pressing said finger against the front matrix of a line while the line is being assembled and transferred, means carried by and movable with the slide for supporting the rear end of an assembled line. 120

line during transfer of the same, and means for moving said first named finger out of the path of the assembled line of matrices as the line reaches a desired position.

5 5. In a mechanism of the kind described, a transfer slide, a block slidably mounted thereon, a spring for yieldingly holding said block against movement relative to the slide, a finger pivotally mounted on the block for supporting the front end of a line of matrices, and a second finger slidably mounted on said slide for supporting the rear end of the line.

10 6. In a mechanism of the kind described, a transfer slide and means for moving the same forward and backward, a block slidably mounted on said slide, a spring operatively connected to said slide and block for yieldingly holding said block against movement

15 20 relative to the slide, a finger pivotally mounted on said block for supporting the front end of a line of matrices, a latch on said block for holding the finger in position to support the matrices, a spring tending

25 30 to move the finger out of the path of the matrices, means operating on the forward movement of the slide to withdraw the latch to permit said finger to move out of the path of the matrices, and means operating on the backward movement of the slide to restore said finger to matrix supporting position.

7. In a mechanism of the kind described, a slide, a block slidably supported thereon, a rod secured to said block and extending along said slide, means on the slide for guiding said rod, a spring secured to said rod and said slide for yieldingly holding said block against movement relative to the slide, means on said block for supporting the front end of a line of matrices, means movably mounted on said slide for supporting the rear end of the line, and means for moving the slide.

40 45 8. In a mechanism of the kind described, a receptacle for receiving matrices to form a line, a transfer slide, a block slidably mounted thereon, a finger pivotally mounted on said block and normally positioned within

50 55 said receptacle for supporting the front end of a line of matrices, means for pressing matrices toward said finger as they are delivered to said receptacle, means for yieldingly urging said finger toward said last named means, a spring pressed pawl arranged in the side of said receptacle and projecting within the same to hold the rear matrix of a line upright during assembling of the line, a second finger on said slide, means for moving said slide, and means for positioning said second finger against the rear end of the line of matrices when said slide moving means is operated.

60 65 9. In a mechanism of the kind described having a receptacle for receiving matrices

and space bands to form a line, a transfer slide, means for moving said slide, a movable finger adapted to be positioned to support the rear end of the assembled line, and means operated by the slide moving means for positioning said finger against the rear end of the assembled line.

70 10. In a mechanism of the kind described having a receptacle for receiving matrices and space bands to form a line, a transfer slide, means for moving the slide, a finger slidably supported on said slide, and means operated by the slide moving means for moving said finger into position to support the rear end of the assembled line of matrices.

75 11. In a mechanism of the kind described having a receptacle for receiving matrices and space bands to form a line, a transfer slide, means for moving the slide, a finger mounted on said slide, means for moving said finger into position to support the rear end of the assembled line, said last named means being operated by movement of said slide moving means.

80 12. In a mechanism of the kind described having a receptacle for receiving matrices to form a line, a transfer slide, means on the slide to support the front end of the assembled line, a finger slidably supported on said slide, a lever for moving said finger into position to support the rear end of the assembled line, means for moving said slide, and means associated with said last named means for operating said lever.

85 13. In a mechanism of the kind described having a receptacle for receiving matrices to form a line, a transfer slide, means thereon for supporting the front end of an assembled line, a finger slidably mounted on said slide, a lever for moving said finger into position to support the rear end of an assembled line, means for moving said transfer slide, a lost motion connection between said last named means and said slide, and means associated with said slide operating means 90 100 for causing movement of said lever before said slide is caused to move.

105 14. In a mechanism of the kind described having a receptacle for receiving matrices to form a line, a transfer slide, a finger mounted thereon and normally positioned beneath the matrix receptacle, means for raising said finger to position the same at the rear of an assembled line, means for operating said slide, and means associated 110 115 with said last named means for raising said finger before movement of the slide takes place.

120 15. In a mechanism of the kind described having a receptacle for receiving matrices to form a line, a transfer slide, a finger mounted thereon and normally positioned beneath the matrix receptacle, a lever for raising said finger into position at the rear of an assembled line, means for moving said slide, 125 130

and means associated with said last named means for contacting with and moving said lever before movement of the slide takes place.

- 5 16. In a mechanism of the kind described having a receptacle for receiving matrices to form a line, a transfer slide, a reciprocating link connected thereto for operating the same, a lost motion connection between said 10 link and slide whereby said link may move to a limited extent without moving said slide, a finger mounted on the slide, and normally positioned beneath the matrix receptacle, but adapted to be raised to support the 15 rear end of a line of matrices, a lever for operating said finger, means for raising said lever and finger during the limited movement of said link toward said slide and for permitting the same to return to their normal position during such limited movement in the opposite direction and means on the 20 slide for supporting the front end of an assembled line.

17. In a mechanism of the kind described 25 having a receptacle for receiving matrices to form a line, a transfer slide, means thereon for supporting the front end of a line of matrices, a finger for supporting the rear end of a line of matrices, mechanism for operating said transfer slide, a starting key for initiating the movement of said mechanism, and means automatically operated upon the movement of said mechanism for positioning said finger against the rear end of 30 the line of matrices.

18. In a mechanism of the kind described having a receptacle for receiving matrices to form a line, a transfer slide, a finger thereon for supporting the front end of a 35 line of matrices, a second finger thereon for supporting the rear end of a line of matrices, power operated means for moving said slide, and means operable by said slide moving means for positioning said second finger against the rear of the line of matrices when 40 said slide moving means are actuated.

19. In a mechanism of the kind described, a transfer slide, means thereon for supporting a line of assembled matrices, means for 45 moving said slide forward to transfer the matrices and backward to its initial position, a latch for holding the slide in its initial position, and means operable by said slide moving means for releasing the latch 50 before forward movement of the slide begins.

20. In a mechanism of the kind described, a transfer slide, means thereon for supporting a line of assembled matrices, means for 55 moving said slide forward to transfer the matrices and backward to its initial position, a lost motion connection between said slide and said moving means whereby the

latter may move relative to the former, a latch for holding said slide in its initial position, and means operable by the relative motion between said slide and moving means for releasing said latch before forward movement of the slide begins.

21. In a mechanism of the kind described 70 having a receptacle for receiving matrices to form a line, a transfer slide, means thereon for supporting the front end of a line of matrices, a finger on said slide, a lever for moving said finger into position to support the rear end of a line of matrices, means for moving said slide forward to transfer the matrices and backward to its initial position, a latch for holding said slide in its initial position, and means operable by 75 movement of said slide moving means for releasing said latch and for operating said finger-moving lever before forward movement of said slide takes place.

22. In a mechanism of the kind described 80 having a receptacle for receiving matrices to form a line, a transfer slide, a finger on said slide for supporting the front end of a line of matrices, a second finger movably mounted on said slide and normally positioned beneath the matrix receptacle, a lever for operating said second finger, means for moving said slide forward to deliver a line of matrices and backward to its original position, means operable by the forward movement of said slide moving means to actuate said lever and position said second finger at the rear of a line of matrices, said lever and second finger arranged to return by gravity 85 to their normal position when said slide moving means moves backward to its original position.

23. In a mechanism of the kind described having a receptacle for receiving matrices to form a line, a transfer slide, a finger on said slide normally positioned below the matrix receptacle, a lever pivoted intermediate of its length on said slide, the front end of said lever being connected to said finger, means connected to said slide for operating the same, and means associated with said slide moving means for contacting with the rear end of said lever to move the same and position said finger at the rear of a line 90 of matrices.

24. In a mechanism of the kind described, a transfer slide, a connecting link pivoted thereto, a slide operating rod connected to said link, an abutment against which said link is positioned when said rod is moved forwardly, a second abutment against which said link is positioned when said rod is moved rearwardly, and means for operating said rod to move said slide.

In testimony whereof I affix my signature. 125
FREDERICK W. LETSCH.
